(57) **CLAIM**

The ornamental design for a folding grate, as shown and described.

DESCRIPTION

FIG. 1 is a top view of the invention showing an open position;

FIG. 2 is a bottom view thereof;

FIG. 3 is a side view thereof;

FIG. 4 is an opposite side view thereof;

FIG. 5 is a front view thereof;

FIG. 6 is a back view thereof;

FIG. 7 is a perspective view thereof;

FIG. 8 is a partially exploded top view of the invention showing a closed position;

FIG. 9 is a partially exploded bottom view of FIG. 8;

FIG. 10 is a partially exploded side view of FIG. 8;

FIG. 11 is a partially exploded opposite side view of FIG. 8;

FIG. 12 is a partially exploded front view of FIG. 8;

FIG. 13 is a partially exploded back view of FIG. 8; and,

FIG. 14 is a partially exploded perspective view of FIG. 8.
